UNITED STATES PATENT OFFICE.

WILLIAM H. RUSSELL, OF NEW CITY, AND HARVEY C. EARL, OF NEW YORK, N. Y.

INHALER.

SPECIFICATION forming part of Letters Patent No. 516,448, dated March 13, 1894.

Application filed April 27, 1893. Serial No. 472,099. (No model.)

To all whom it may concern:

Be it known that we, WILLIAM H. RUSSELL, residing at New City, in the county of Rockland, and HARVEY C. EARL, residing at New York, in the county of New York, State of New York, citizens of the United States, have invented new and useful Improvements in Demephitzing Devices, of which the following is a specification.

- 10 The object of this invention is a demephitzing device which can be readily used for charging the air which a person inhales with a suitable demephitzing substance or for charging the air in a railroad car or in a room 15 or house with such demephitzing substance, the peculiar and novel construction of said device being pointed out in the following specification and claim and illustrated in the accompanying drawings, in which—
- 20 Figure 1 is a longitudinal section when the valves are closed. Fig. 2 is a similar view when the valves are open. Fig. 3 is a front elevation of a hot air furnace partly in section illustrating the application of the demephitzing device for charging the air passing into a house with a demephitzing substance.

In the drawings the letter A designates a receptacle which may be made of glass or any 30 other suitable material and the size and shape of which must be changed according to the place where or the purpose for which it is to be used. If it is to be used for the purpose of charging the air which a person inhales, with a suitable demephitzing substance, the receptacle may be made cylindrical and small enough to be carried in the pocket and a number of such cylindrical receptacles can be used for charging the air in 35 a railroad car or in a room with the demephitzing substance, but if the object is to charge the air in a house with the demephitzing substance, the receptacle must be made sufficiently large for this purpose. Said receptacle is charged with an absorbent material 40 B which is saturated with the demephitzing substance and the ends of the receptacle are provided with valves C D respectively so that when these valves are closed, no air can

pass through the receptacle but when the valves are open and one end of the receptacle is applied to the nostrils, the air inhaled has to pass through the absorbent material B so that it becomes charged with the demephitzing substance before it reaches 55 the nostrils.

The receptacle A is composed of a tube a open at both ends and provided with caps b b' which are provided with seats c, d, respectively for the valves C D. These valves are 60 mounted on a common rod E, and the valve C opens outward while the valve D opens inward, so that when the rod E is moved to the position shown in Fig. 1, both valves are closed, and when the rod E is moved to the 65 position shown in Fig. 2 both valves are open. The caps b b' are secured to the ends of the tube a in such a manner that they are retained in position either by friction or otherwise, but they can be adjusted in order to 70 bring the seats c, d, in the proper relation toward the valves C D. If desired, however, the valves C D may be adjustably secured on the rod E. The tube a is provided with cross-bars e which form guides for the rod E, 75 and which also serve to retain the absorbent material B in position.

In order to apply the demephitzing device to a hot air furnace the pipe F (Fig. 3) through which the cold air enters, is provided 80 with an enlarged chamber G into which the receptacle A is placed, and this receptacle is provided at its ends with valves C D mounted on the rod E to which the required motion can be imparted by a lever or any other 85 means so as to open or close the valves C D. If the valves are opened, the cold air which enters through the pipe F is charged with the demephitzing substance and the air so charged passes up into the house and through 90 the registers into the various apartments.

What we claim as new, and desire to secure by Letters Patent, is—

A demephitzing device, consisting of a tube a charged with a demephitzing substance and having end caps b and b' provided respectively with the valve seats c and d, a rod E extending continuously through 95

the tube and through the valve seats in the said caps, and valves C and D secured to the rod in juxtaposition to the ends thereof so that both valves open or close simultaneously by moving the rod lengthwise, substantially as described.

5 In testimony whereof we have hereunto set

our hands in the presence of two subscribing witnesses.

WILLIAM H. RUSSELL.
HARVEY C. EARL.
